UNITED STATES PATENT OFFICE.

WILLIAM H. NEHER, OF INGLEWOOD, CALIFORNIA.

CRUDE-OIL GENERATOR

No. 814,866.

Specification of Letters Patent. Patented March 13, 1906.

Application filed January 24, 1905. Serial No. 242,510.

To all whom it may concern:

Be it known that I, WILLIAM H. NEHER, a citizen of the United States, residing at Inglewood, in the county of Los Angeles and State of California, have invented a new and useful Crude-Oil Generator, of which the following is a specification.

This invention relates to an apparatus for converting crude oil or distillate into gas for use in explosive-engines, the necessary heat for the conversion of the product into gas being derived from the exhaust-gas of the engine.

In apparatus of this character as ordinarily constructed the suction within the generator produced by the engine draws much unconverted oil or distillate into the engine along with the gas; and the main object of the present invention is to provide a construction whereby the suction from the engine will draw only the gas from the generator and to increase the efficiency of the generator, thereby increasing the power of the engine and also obviating the accumulation of oil in the engine.

Another important object of the invention is to provide a construction such that by the removal of one part of the generator and without the disconnection of any pipe or other appurtenance of the device the interior parts of the generator may be exposed, so that they may be easily cleaned.

Another object of the invention is to provide a novel and unique means for distributing the oil over the dome of the vaporizing member.

Another important object of the invention is to provide efficient means for controlling the amount of heat admitted to the generator and to prevent the overheating of the generator by that amount of the exhaust which is not being utilized for converting the oil into gas.

Other objects and advantages of the invention will appear from the following description.

The accompanying drawings illustrate the invention, and, referring thereto, Figure 1 is a vertical cross-section through the generator, showing it connected with the cylinder of a gas-engine. Fig. 2 is a side elevation of the generator with the covering-dome lifted, so as to expose the interior parts, and illustrates the convenient disposition and exposure of the interior parts, allowing the easy cleaning thereof. Fig. 3 is a cross-section on the line

X³ X³ in Fig. 1. Fig. 4 is a side elevation of the retort-dome. Fig. 5 is a vertical section on the line X⁵ X⁵ in Fig. 2.

The generator comprises a base 1, the upper portion of which has a cup 2, which is connected by a neck 3 with a horizontal chamber 4, having tubular extensions 5 and 6.

The tubular extension 5 is connected by a suitable flange-coupling 7 with a pipe 8, which is connected with the cylinder 9 of the engine and which conducts the exhaust-gas from the engine to the chamber 4. The tubular extension 6 has screwed thereto a pipe 10, through which the exhaust-gas is discharged from the generator after it has performed its duty therein. A covering-dome 11 is detachably fastened to the cup 2 by bolts 12, preferably having thumb-nuts 13, so that the dome 11 may quickly be removed from the generator without requiring the use of tools. The interior of the dome 11 may be termed the "vaporizing-chamber."

Formed preferably integral with the neck 3 and extending upwardly therefrom is a web 14, the lower edge of which lies substantially in line with the upper walls of the tubular extensions 5 and 6, the lower part of the web 14 forming a partition 15, which divides the neck 3 into two sections, an inlet-passage 16 and an outlet-passage 17. The bottom of the cup 2 near the neck 3 is provided with an annular groove 18, in which nests the lower rim or edge of a conical vaporizing member 19, there being a bolt 20 attached to the upper edge of the web 14 and extending up through the top of the vaporizing member 19 and having a nut 21 for retaining the vaporizing member 19 in place, but allowing ready removal of the vaporizing member when it is desired.

The web 14 is wedge-shaped, so that its vertical edges closely fit the conical vaporizing member 19, as shown in Fig. 5. Thus when the vaporizing member 19 is drawn down into place its walls tightly hug the web 14, dividing the lower part of the vaporizing member 19 into two sections 22 and 23, the section 22 communicating with the passage 16 and the section 23 communicating with the passage 17. The dome 11 covers and surrounds the vaporizing member, and when the dome is removed the vaporizing member protrudes from the base so that its top and sides are free and exposed and may be most effectually cleaned.

Arranged on the wall of the vaporizing member 19 is a series of inclined horseshoe-

shaped flanges 24. The ends of the flanges 24 are relatively narrow and lie apart slightly, as shown, forming a space 25, while the opposite or bowed part of each flange is wider. 5 The flanges 24 are so arranged that the wide portion of a flange lies directly under the narrow portion and space 25 of the flange next above, and the flanges are arranged in two sets, one set being inclined in one direction and the other set being inclined in the opposite direction, alternate flanges being parallel. An oil-pipe 26 extends up into the inside covering-dome 11, and its upper end is curved and points downwardly, so as to discharge oil upon the top of the retort 19, the oil-pipe 26 receiving its supply of oil from an overflow-cup (not shown) and being provided with a suitable valve 27 for regulating the flow of oil therethrough. The lower part of 15 the cup 2 is provided with a drain-cock 28. A pipe 29 extends up through the cup 2 and into the lower part of the dome 11 for the purpose of admitting air to the interior of the dome to combine with the vaporized oil, the pipe 29 being provided with a suitable valve 30 for regulating the admission of air to the interior of the dome. A flap-valve 31 is hinged to the lower edge of the partition 15 and may be moved into the position shown 20 in dotted lines in Fig. 1, in which it completely closes the passage 16, or it may be moved into a position resting upon the lower wall of the chamber 4, as shown, or it may be moved into any position intermediate of these two extreme positions. The valve 25 may be operated by any suitable means, such as the handle 50, which slides over a sector 51 and which is adjustably held in position thereon by means of the clamp-screw 52. A pipe 32 extends up through the cup 2 inside the dome 11, and its upper end terminates at a point slightly below the upper part of the dome 11, the mouth of the pipe pointing upwardly, as shown, the lower end being 30 connected by a pipe 33 with a T 34, one branch of the T 34 being connected by a pipe 35 with the cylinder 9 and the other branch of the T 34 having connected thereto a pipe 36, through which air is delivered to the pipe 35, the pipe 36 being provided with a suitable valve 37 for controlling the admission of air and the pipe 33 being provided with a suitable valve 38 for controlling the admission of gas to the engine. The upper end of 35 the dome 11 is preferably provided with an eyebolt 39, by means of which it may readily be lifted.

In operation oil is admitted through the pipe 26 into the vaporizing-chamber and 40 dropping down from the upper end thereof onto the vaporizing member 19 spreads out and flows down the inclined flange 24, flowing around each side of the vaporizing member, thence down through the space 25, and onto 45 the wide portion of the next lower flange 24,

then flowing down both sides of the flange and to the other side of the retort and thence down through the space onto the wide part of the next lower flange and thence from that flange to the fourth flange and from the 70 fourth flange to the fifth, and so on down, the oil being carried in a tortuous double path down the vaporizing member, traversing the walls of the vaporizing member back and forth in its passage down. 75

The exhaust-gas from the cylinder 9 is conducted through the pipe 8 to the tubular extension 5, and with the valve 31 open, as shown in Fig. 1, it passes up through the passage-way 16 into the section 22 of the vaporizing member, thence over the top of the web 14, as indicated by the arrows, thence down the other side of the web through the section 23 and through the passage-way 17 into the tubular extension 6, and thence out 80 through the pipe 10. The exhaust-gas in passing through this circuit highly heats the vaporizing member 19, and this heat is imparted to the oil which is working down on the outside of the vaporizing member, and 85 the oil is thus formed into a gas, which fills the dome 11. The upper part of the dome contains the rarer and purer gas combined with air, which enters through the pipe 29, and when the engine takes a suction-stroke 90 95 gas and air from the upper part of the dome are sucked through the pipe 32 into the cylinder of the engine, combining with it, however, before being admitted to the engine, a further amount of air, which has been admitted through the pipe 36, whereby the 100 proper explosive mixture is produced.

It is important to arrange the upper end of the pipe 32 near the upper end of the dome, so that it will suck in only the pure gas and 105 allow the unconverted oil in the lower part of the dome to remain on the vaporizing member and be fully converted into gas. This not only increases the power of the engine by admitting thereto only the pure gas, but also 110 by eliminating all particles of oil or other unconverted products of the crude fuel prevents accumulation of matter in the engine which would clog and impair the action of the same. 115

It is very important that the pipe 32 suck down from the top, as it then creates a suction in the upper part of the covering-dome, which draws gas in from the side wall of the covering-dome and results in promoting a thorough circulation of gas within the dome. 120 If the mouth of the pipe were arranged to suck upwardly, it would draw gas directly up from the center of the dome, thus short-circuiting and allowing gas to pocket around the side wall of the dome inertly, which 125 would defeat the best results and prevent the gas being delivered steadily and continuously of an even quality.

The valve 30 should be so regulated as to supply the proper amount of air to the dome 130

to form with the oil-vapor the desired explosive mixture.

In order to drain the cup 2 and remove any unvaporized oil or other matter which has accumulated therein, the waste-cock 28 is provided.

When it is desired to clean the apparatus, the thumb-nuts 13 may be loosened, and the dome 11 may be lifted up, as shown in Fig. 2, 10 thereby exposing the outside of the vaporizing member 19 with its flanges and also exposing the interior of the cup 2, and as these parts are the only parts with which the oil comes into contact after leaving the supply-pipe 26 the generator may readily be cleaned thoroughly.

A great advantage is the facility with which the dome 11 can be removed and the perfect exposure of the oil-covered parts, thus 20 providing for ready cleaning.

So far as I am aware this is the first apparatus of this character in which a single cover completely houses the oil-covered parts, covering the top and also all sides of the oil-covered parts, which cover can be removed without disconnecting or removing any attachments or other parts and which when removed gives a complete exposure of the oil-covered parts, which when the cover is removed protrudes from the rest of the apparatus. The oil-retaining flanges thus being exposed on all sides and not hedged by any part of the generator may be effectually cleaned.

Another important feature is that practically a perfect control of the heat delivered to the vaporizing-chamber by the valve 31 is obtained, as when it is in the position shown in Fig. 1 all of the exhaust from the engine is 30 forced to travel through the vaporizing member, while by closing the valve slightly that part of the exhaust which is not admitted by the valve will pass underneath the valve and freely away from the generator, passing directly out through the pipe 6, and thus only that part of the exhaust which is required is admitted by the valve 31. In this manner the amount of heat delivered to the vaporizing member and vaporizing-chamber may 40 be perfectly controlled, while by completely closing the valve 31 all of the exhaust-gas, with its heat, will pass directly horizontally through the chamber 4 and out through the pipe 10, and as the neck 3 supports the cup 2 and dome 11 with interior vaporizing member 19 considerably above the horizontal chamber 4 and tubular extensions 5 and 6 none of the heat from the exhaust-gas is imparted to the vaporizing member and vaporizing-chamber when the valve 31 is closed, as 50 the exhaust-gas passes out in the most direct manner, and there is considerable distance between this line of passage of the gas and the vaporizing-chamber and retort.

65 The most important advantage of having

the retort and vaporizing-chamber separated from the chamber 4 by the neck 3 is that when only part of the exhaust-gas is used for heating only that part of the gas which is allowed to pass up through the neck by the valve heats the retort, and an even or uniform distribution of heat throughout the vaporizing-chamber is secured, and so far as known I am the first to provide an apparatus of this character through which all of the exhaust-gas passes in which the retort and vaporizing-chamber are evenly heated throughout, due to the provision of means whereby all or any part only of the exhaust-gas is allowed to come into contact with the 70 retort.

What I claim is—

1. A generator comprising a base-chamber, a vaporizing member above the base-chamber, a covering-dome housing and nesting with the vaporizing member, suitable means unattached to the covering-dome for conducting exhaust-gas through the vaporizing member and for conveying fuel to the interior of the covering-dome and for conveying 85 gas from the interior thereof, and for passing air in an upwardly-directed current into the dome.

2. A generator comprising a base-chamber, a vaporizing member detachably mounted 95 above the same, a removable covering-dome housing and nesting with the vaporizing member and completely exposing the same when removed, suitable means unattached to the covering-dome for conducting exhaust-gas through the vaporizing member and for conveying fuel to the exterior of the vaporizing member and removing gas from the interior of the covering-dome.

3. A generator comprising a base with a chamber, a cup above the chamber and connected therewith by a neck, a vaporizing member mounted upon the base and a covering-dome resting upon the cup and housing the vaporizing member, and means for conveying exhaust-gas to said chamber.

4. A generator comprising a base with a chamber, a cup with its rim slightly above the top of the base and connected with the chamber by a neck, a vaporizing member detachably mounted upon the base, and a covering-dome resting upon the rim of the cup and housing the vaporizing member, and means for conveying exhaust-gas to said chamber.

5. A generator comprising a base with a chamber, a cup with its rim slightly above the top of the base and connected with the chamber by a neck, a vaporizing member detachably mounted upon the base, a covering-dome resting upon the cup and housing the vaporizing member, a fuel-supply pipe extending up through the base inside the covering-dome and discharging upon the vaporizing member, a gas-pipe extending up 130

through the base inside the covering-dome and arranged with its mouth opening upwardly near the top of the covering-dome, and means for conducting exhaust-gases through 5 the vaporizing member.

6. A generator comprising a base with a chamber, a cup with its rim slightly above the top of the base and connected with the chamber by a neck, a vaporizing member 10 detachably mounted upon the base, a covering-dome resting upon the rim of the cup and housing the vaporizing member, a fuel-supply pipe extending up through the base inside the covering-dome and discharging upon 15 the vaporizing member, a gas-pipe extending up through the base inside the covering-dome and arranged with its mouth opening upwardly near the top of the covering-dome, means for conducting exhaust-gases through 20 the vaporizing member, and a valve within said chamber for regulating the amount of exhaust-gas admitted to the vaporizing-chamber.

7. A generator comprising a base-chamber, 25 a vaporizing member above the base-chamber, a covering-dome housing and nesting with the vaporizing member, and a gas-pipe extending up through the base inside the covering-dome and arranged with its mouth 30 facing the top of the covering-dome.

8. A vaporizing member comprising a conical dome, and horseshoe-shaped flanges thereon.

9. A vaporizing member comprising a conical dome, and horseshoe-shaped flanges thereon arranged in two sets, the flanges of one set being parallel with one inclined plane, and the flanges of the other set being parallel 35 with an oppositely-inclined plane.

10. A generator comprising a base with a chamber, an upwardly-projecting web formed integral with the base, and a vaporizing member detachably mounted on the base, the edges of the web closely fitting the walls of 45 the vaporizing member and forming two passages therein, and means for conducting exhaust-gas to said chamber.

11. A generator comprising a base with an annular groove, an upwardly-projecting web 50 formed integral with the base, a vaporizing member with its rim nested in the groove, a

bolt extending from the web up through the vaporizing member with a nut thereon for engaging the vaporizing member.

12. A generator comprising a base with a 55 chamber, a cup connected therewith by a neck, a dome with its rim detachably fastened to the rim of the cup, a web formed integral with the base and extending up into the dome, a vaporizing member detachably 60 fastened to the cup and closely fitting the web, a web extending down into the chamber in the base, a valve thereon, a fuel-pipe extending through the base into the covering-dome and discharging upon the top of 65 the vaporizing member, an air-pipe extending up through the base into the dome, and means for conducting exhaust-gas to and from the vaporizing member.

13. A generator comprising a base, means 70 for conducting exhaust-gas through the base, a vaporizing-chamber situated near the base, a vaporizing member in the vaporizing-chamber, a removable dome covering the vaporizing member and nested therewith and a 75 valve in the base for controlling the amount of exhaust-gas admitted to the vaporizing member, and means for conducting that part of the exhaust-gas which is not admitted to the vaporizing member by the valve, freely 80 away from the generator.

14. A generator comprising a base, means for conducting exhaust-gas through the base, a vaporizing-chamber situated near the base, a vaporizing member in the vaporizing-chamber, a removable dome covering the vaporizing member and nested therewith, a valve in the base for controlling the amount of exhaust-gas admitted to the vaporizing member and a drain-cock for the vaporizing-chamber, and means for conducting that part 85 of the exhaust-gas which is not admitted to the vaporizing member by the valve, freely 90 away from the generator.

In testimony whereof I have hereunto set 95 my hand, at Los Angeles, California, this 16th day of January, 1905.

WILLIAM H. NEHER.
